United States Patent

Des. 235,817
Patented July 15, 1975

235,817

BRASSIERE

Jack J. La Cascio, Bayonne, N.J., assignor to Rapid-American Corporation, New York, N.Y.

Continuation-in-part of design application Ser. No. 359,933, May 14, 1973, now Patent No. 232,007.
This application July 5, 1974, Ser. No. 486,024
The term of this patent subsequent to July 9, 1988,
has been disclaimed

Term of patent 14 years

Int. Cl. D2—01

U.S. Cl. D2—24

FIG. 1

FIG. 2

FIG. 1 is a perspective front view of a brassiere showing my new design, the side and back panels thereof being conventional; and

FIG. 2 is an inside plan view.

This is a continuation-in-part of design application Ser. No. 359,933, filed May 14, 1973, and now Pat. No. D. 232,007.

I claim:

The ornamental design for a brassiere, substantially as shown and described.
